DEMONSTRATION APPARATUS

Joseph F. Putnam, Berkeley, and Ellis R. Abbe, Richmond, Calif., assignors, by mesne assignments, to Standard Oil Company of California, San Francisco, Calif., a corporation of Delaware

Application November 25, 1932, Serial No. 644,162

5 Claims. (Cl. 35—16)

This invention relates to physical apparatus and more particularly to one which is adapted to demonstrate to an untrained and unskilled observer the difference in the physical characteristics of two types or grades of lubricant, such as a "gear grease" and a "gear oil" under certain conditions of temperature.

In present automotive lubrication practice, it has been found that a lubricant such as is used for an automobile transmission, for example, which is of the proper viscosity for summer use, when the atmospheric temperature may be at or near 100 degrees Fahrenheit for considerable periods, may become so viscous in winter, when the temperature may be at or below freezing, that it will not properly lubricate the rubbing surfaces, and will also interfere with the shifting of gears. This range of temperature from summer to winter is not unusual in many sections of this country. The obvious procedure is to provide a fairly viscous lubricant for the warm summer period, and, upon the approach of winter, to drain out this lubricant, which may be of the type known to the trade as a "gear grease", and substitute therefor a "gear oil" or lubricant of lower viscosity, or one which will retain its fluidity at low temperatures. This practice is conducive to better lubrication of the relatively moving parts, and also allows the manipulation or shifting of gears to be more easily and safely accomplished.

The logic of this substitution is not easily demonstrated to a driver of an automobile by simple argument or by sales talks, particularly because of the fact that the transition from warm to cool to cold weather is more or less gradual, and the increased effort required to shift gears is not readily observed. The other result, that of improper lubrication, is usually not outwardly apparent at all, unless the concealed parts become so badly worn as to require replacement, as increased noise caused by undue wear is masked by the increased viscosity of the lubricant.

It has been found, however, that the evidence of the physical senses, particularly the "manual" sense of touch or muscular effort, is more convincing to most individuals than a logical argument. Accordingly, a simple and roughly qualitative physical comparison apparatus has been devised for demonstrating the effect of temperature upon the viscosity of different lubricants, which apparatus may be manipulated by the customer to his own satisfaction, thereby convincing him that it is convenient and usually economical to make periodical changes of lubricant as outlined above.

It is an object of this invention to provide a

roughly qualitative physical testing apparatus to demonstrate to an unskilled observer the effect of temperature upon different grades of lubricants.

Another object is to provide an apparatus of this nature which is very simple to construct and to use and which is so cheap that one may be economically installed in every service station of a marketing organization.

A further object is to provide an apparatus in which the manual or muscular sense of the observer is utilized to show roughly the difference in viscosity between two lubricants.

These and other objects will be more fully apparent from the description which follows, and from the accompanying drawing, which forms a part of this specification and illustrates a preferred embodiment of this invention.

In the drawing:

Figure 1 is an end elevation, partly in section, of a comparison device embodying this invention.

Figure 2 is a side elevation of the device shown in Figure 1.

In the drawing, the numeral 11 represents a rectangular metal tank or container, which is divided longitudinally by means of a vertical plate 12 into two identical long, deep and narrow compartments 13 and 14. The tank 11 may be made of galvanized sheet steel or the like and is preferably soldered at all joints to prevent leakage.

A transverse shaft 15 passes through the upper side walls of both compartments 13 and 14 as shown, and may be upset or riveted over at its outer ends 16 to retain it in place. Pivoted to turn freely on shaft 15 are two identical paddles or agitators 17, which may be of hard wood or the like. Paddles 17 may be fitted with metal handles or levers 18 which terminate at their upper ends in knobs 19 to facilitate their operation. If desired, the paddles and handles may be made of one piece of hardwood or metal, and of any desired cross-section, although the square section shown has proved to be quite satisfactory.

Shaft 15 is preferably provided with spacing bushings or washers 20, which serve to space paddles 17 equally from the walls of compartments 13 and 14. A wooden base 21, with a molding 22 may be attached to tank 11, to make it more stable.

In operation, one compartment is filled about half full of one grade of lubricant, as shown by the dotted line A, and the other filled to the same height with the alternative material. Care should be taken that the paddles are equally immersed, in order that a true and representative

result will be obtained. When the two compartments are exposed to and have reached a uniform temperature, for example, that of the outside atmospheric temperature, the viscosity of the materials in the two compartments may be quite different. The operator, to note this difference, and also to note the effect thereof on the ease of shifting the gears of an automobile transmission, for example, merely oscillates first one paddle and then the other, whereupon his "manual" or muscular sense will at once distinguish between the two lubricants, and will convey to him the reasons for changing from one lubricant to the other according to the changes in atmospheric temperature.

This has been found true in practice, and has resulted in greatly increased sale of lubricants, as well as a more intelligent comprehension of the mechanics of this type of lubrication by the 20 customers who have operated the apparatus.

It is obvious that this device may be made with more than the two compartments illustrated for the comparison of a number of lubricants, all of different viscosity-temperature characteristics, and for the same or like purposes as outlined above.

Although a specific construction embodying this invention has been described and illustrated, it is to be understood that the invention is not limited to that specific device, and all such modifications and changes as come within the scope of the appended claims are embraced thereby.

We claim:

1. An apparatus for demonstrating the comparative viscosity characteristics of lubricants, comprising a plurality of lubricant containers, separately pivoted members extending into said containers, each of said members adapted to be independently manually oscillated by an observer, the resistance to said separate oscillation furnishing an index to the viscosity of the lubricant.

45 2. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

50 3. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

55 4. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

60 5. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

65 6. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

70 7. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

80 2. An apparatus for demonstrating the comparative operating characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

85 3. An apparatus for demonstrating the comparative viscosity characteristics of lubricants at a given temperature, comprising two adjacent compartments, a shaft passing through the walls of said compartments, and two agitators independently rotatably mounted on said shaft, one extending into each compartment and definitely spaced from the walls thereof.

90 4. An apparatus for demonstrating the comparative viscosity characteristics of lubricants, consisting of two adjacent rectangular compartments, a shaft passing through the side walls of said compartments near the upper edge thereof, and two similarly shaped agitators independently rotatably mounted on said shaft, one extending into each compartment and definitely spaced from the walls thereof.

95 5. An apparatus for physically demonstrating the effect of temperature upon the viscosity characteristics of lubricants, consisting of two adjacent rectangular compartments, a shaft passing through the side walls of said compartments near the upper edge thereof, two similarly shaped agitators separately mounted on said shaft, one extending into each compartment, and spacing means on said shaft whereby said agitators are equally spaced from the walls of said compartments.

100 JOSEPH F. PUTNAM. 115
ELLIS R. ABEE.

105 45 6. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

110 50 7. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

115 55 8. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

120 60 9. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

125 65 10. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

130 70 11. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

135 75 12. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

140 80 13. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

145 85 14. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.

150 90 15. An apparatus for demonstrating the comparative viscosity characteristics of lubricants, comprising adjacent containers for lubricant, similarly shaped separately pivoted members extending into said containers to substantially equal depths, each of said members definitely spaced from the walls of said containers and adapted to be separately manually oscillated by an observer, the resistance to said separate oscillation furnishing an index to the viscosity of the lubricant.
